J. M. Earls,

Smart Mill

N° 8,904.

Patented Aug. 27, 1852.

UNITED STATES PATENT OFFICE.

JNO. M. EARLS, OF TROY, NEW YORK.

SMUT-MACHINE.

Specification of Letters Patent No. 8,904, dated April 27, 1852.

To all whom it may concern:

Be it known that I, JOHN M. EARLS, of Troy, in the county of Rensselaer and State of New York, have invented a new and Improved Machine for Cleaning Grain; and I do hereby declare that the following is a full and exact description thereof, reference being had to the accompanying drawings and to the letters of reference marked thereon, viz.:

Figure 1 is a sectional elevation of the entire machine. Fig. 2 is a ground plan and elevation of the rubber and ventilator cut through the machine at A, B. a, a, a, a are two sets of spiral arms, one set in the ventilator and the other in the rubber and are made in this form to create a center draft of air for the purpose of driving the chaff and smut downward to the discharge spouts. Fig. 3 is a ground plan and elevation of the scourers, beaters, wings and part of the rubber. The ground plan in this figure is a view of the bottom scourer seen from the lower side. B, B, B, B are four wings extending from the lower scourer to the rubber. These wings are for the purpose of driving the dust and other light stuff through the small openings in the outside or case. c, c, c, c are the beating forks attached to the scourers. These are for the purpose of breaking or beating the hulls and such other substances as adhere to the berries after having been discharged from the rubber. D D are two scrapers attached to the under side of the lower scourer. These scrapers gather the grain as it falls upon the center plate and force it out of the openings in this plate on to the screen aprons.

Fig. 4 is a ground plan and elevation of the blower which runs in the bottom. This blower is made very large for the purpose of producing a strong blast which comes in contact with the grain upon the screens. Fig. 5 is a ground plan and elevation of the concave bottom with the top or body of the machine removed so that the screens and aprons can be seen. e, e, are the screens and aprons which are united and fastened inside of the screen chambers and extending upward to the openings in the middle plate. The screens do not cover the whole of the screen chamber but an opening is left sufficient to let the grain pass over when it slides

down the chamber and discharges at the bottom of the machine. f is a bridge pot that 55 the lower end of the shaft runs in. G is the oil pipe which supplies the step with oil from the outside of the machine. The elevation in Fig. 5 shows the bottom cut through at the line H H and exhibits the inside. 60

Fig. 6 is a ground plan and elevation of one half of the case removed from the machine. h is the journal and oil box. i, i are the frames which project from the bottom plate and set upon the edge of the screen chambers and form a base for the smut spouts. j, j, are the openings which admit the grain into the machine. The elevation in this figure is an inside view of the case. 65 k, k, are a series of circular zigzag grating projections upon the under side of the head plate which works in unison with the rubber which rub and grate the berry before coming in contact with the beating and scouring 70 surfaces. 75

Fig. 7 is an elevation of the entire machine with the smut spouts attached. These spouts are provided with openings near the top and a slide for opening or closing the 80 same for the purpose of increasing or diminishing the blast. These smut spouts are shown on Figs. 1 and 7 and are marked W. The smut chaff and other light stuff is blown out, all together, through the smut 85 spouts w, w and the grain passes over the end of the screen e and discharges through the bottom.

Thus having fully described my machine I wish it to be understood that I do not 90 claim as new a "perforated case" the same having been heretofore in use, neither do I claim a spike rubber nor a ventilator with spiral arms, nor scourers made of sheet or other metal, nor do I claim the oil box at the 95 top of the machine nor the oil pipe for the lower bearing of the shaft. But

What I do claim as new and desire to secure by Letters Patent is—

1. The projecting screen chambers, in combination with the arrangements for separating the rubbing chamber from the fan chamber, whereby the grain is prevented from being affected by the blast from the fan chamber, while it is passing through the rubbing 105 chamber, and is only brought in contact

with the current of air where it ascends to take away the chaff and other impurities substantially as herein set forth.

2. I also claim in combination with the 5 scouring surfaces, the beating forks, for the purpose of beating the grain and breaking the hulls while falling from the rubber to

the scourers, whereby the berries are more effectually cleaned from adhering impurities as herein set forth.

JOHN M. EARLS.
